VARIABLE PHASE SHIFT SELECTOR

Fred T. Pitts, Rockville, and Tommy S. Weaver, Arnold, Md., assignors, by mesne assignments, to the United States of America as represented by the Secretary of the Navy

Filed June 29, 1962, Ser. No. 207,169

1 Claim. (Cl. 333—31)

The present invention relates to a phase shifter selector and more particularly to a variable phase shifter selector that will rapidly select 0° or 180° relative phase.

Various devices and schemes have been employed in the past for selecting a relative phase shift of a transmitted signal wave. In one method, the input power is divided equally into two lines, one of which is an integral number of half wavelengths (180 electrical degrees) longer than the other. The appropriate shift of either 0 or 180 electrical degrees is accomplished by means of switches, one of which is in each line. This method, however, has several inherent disadvantages. For one thing, there is considerable power loss in such a device, and also, the use of isolators is required. Furthermore, there is considerable difficulty in achieving phase accuracy.

In the present invention, a pair of transmission lines are provided between an input connector and an output connector with one transmission line being a half wavelength longer than the length of the other transmission line. A diode switch is provided in each transmission line and the lengths of each line between the input connector and the diodes are integral numbers of half wavelengths. Thus each switch, when off, will present an open circuit at the input point and thus not introduce any shunt reactance on the selected line. Therefore, it is possible to eliminate the power divider and the isolators. In order to avoid extremely close tolerances on the mechanical parts of the selector, the phase shifter selector is made variable by providing a movable trimmer bar for one of the transmission lines.

It is therefore a general object of the present invention to provide an improved phase shift selector.

Another object of the present invention is to provide an improved selector for selecting either 0 or 180 degrees relative phase shift of a transmitted signal wave.

Still another object of the present invention is to provide a relative phase shift selector that has an extremely fast switching time.

Yet another object of the present invention is to provide an improved phase shifter that is simple to manufacture and has a minimum number of parts.

Other objects and advantages of the present invention will be readily appreciated as the same becomes better understood by reference to the following detailed description when considered in connection with the accompanying drawing in which like reference numerals designate like parts throughout the figures thereof and wherein:

FIGURE 1 is a diagrammatic view of one type of phase shift selector;

FIGURE 2 is a diagrammatic view of a preferred embodiment of the present invention; and

FIGURE 3 is an isometric view of a preferred embodiment of the present invention.

Referring now to the drawing, there is shown in FIGURE 1, a power divider 11 having an input line 12 and two transmission lines 13 and 14 connected thereto. Transmission line 14 is an integral number of half wavelengths (180 electrical degrees) longer than transmission line 13. Isolators 15 and 16 are provided in lines 13 and 14, respectively. Also, switches 17 and 18 are pro-

2

vided in lines 13 and 14, as shown, and the two transmission lines are connected to a single output line 19.

In operation of the embodiment shown in FIGURE 1 of the drawing, input power is divided equally by the power divider 11 into each of the transmission lines 13 and 14. With switch 18 in the open position and switch 17 in a closed position, the power being transmitted through transmission line 13 has a relative phase shift of zero degrees at the output line 19. When it is desired to provide a relative phase shift of 180 degrees, switch 17 is opened and switch 18 is closed, and the input power is transmitted from power divider 11 through transmission line 14 to output line 19.

Referring now to FIGURES 2 and 3 of the drawing, which show a preferred embodiment of the present invention, there is shown an input connector 21 and an output connector 22 to which transmission lines 23 and 24 are connected. Connectors 21 and 22 might be of the coaxial type, and are supported by a suitable frame or housing 25. Transmission lines 23 and 24 are supported by suitable cross-braces 26 and 27, which can be secured to frame 25. Switches 28 and 29 are provided in transmission lines 23 and 24, respectively. By way of example, switch 28 might be comprised of crystal diodes 31 and 32 which are connected to a bias pulse source through connector 33; and likewise switch 29 might be comprised of crystals diodes 34 and 35 that are connected to a bias pulse source through connector 36. As shown in FIGURE 2 of the drawings, the distance between input connector 21 and switch 28 is equal to an integral number of half wavelengths, and the distance between input connector 21 and switch 29 is one half wavelength longer than the distance between input connector 21 and switch 28. A trimmer bar 37, of suitable metal, is provided near transmission line 24, and this bar 37 is threadedly engaged with shaft 38 that is provided with a knob 39. Trimmer bar 37 is provided with a pair of feet 41 and 42 that slidably engage with transmission line 24 in order to prevent rotation of trimmer bar 37 when knob 39 is rotated.

In operation of the embodiment shown in FIGURES 2 and 3 of the drawing, when switch 28 is in a closed position and switch 29 is in an open position, an input signal wave at input connector 21 will be transmitted through transmission line 23 to output connector 22. The transmitted signal will have a relative phase shift of zero degrees. When it is desired to provide a relative phase shift of 180 degrees, switch 28 is opened and switch 29 is closed, and the input signal is transmitted from input connector 21 through transmission line 24 to output connector 22. As the accuracy of the phase shift is a function of the length of transmission line 24, trimmer bar 37 is provided to adjust the effective length of transmission line. As handwheel 39 is rotated and trimmer bar 37 is moved nearer to transmission line 23, the effective length of transmission line 23 is shortened, and likewise, when trimmer bar 37 is moved away from transmission line 23 the effective length of transmission line 23 is lengthened.

The diodes in switches 28 and 29 are polarized such that the application of a bias pulse at a common point will energize one switch. That is, a bias pulse applied at connector 33 will energize diodes 31 and 32 and a bias pulse applied at connector 36 will energize diodes 34 and 35. Direct current returns for the diodes consist of quarter wavelength short circuits which are assembled into the input and output connectors.

It can thus be seen that the present invention provides an improved phase shifter selector that will rapidly select one of two relative phases.

While there has been described a preferred embodiment of the present invention, it will be obvious to those

skilled in the art that various changes and modifications may be made therein without departing from the scope of the invention and it is to be understood, that within the scope of the appended claims, the invention may be practiced otherwise than as specifically described.

What is claimed is:

A variable phase shift selector comprising:
an input connector,
an output connector,
a first transmission line of predetermined length, 10
a second transmission line having a length which is a
half wavelength longer than the length of said first
transmission line,
first and second crystal diode switches connected one
each in each said transmission line, said first crystal
diode switch being connected an integral number of
wavelengths from said input connector and said sec- 15
ond switch being connected an integral number of

wavelengths plus a half wavelength from said input connector, and
means for adjusting the wavelength of said second transmission line whereby a precise 180 degrees phase shift of power applied at said input connector is obtained.
